US00D942875S

(12) **United States Design Patent** (10) Patent No.: **US D942,875 S**
Shao et al. (45) Date of Patent: ** Feb. 8, 2022

(54) **LASER LEVEL**

(71) Applicant: **Aukey Technology Co., Ltd**, Shenzhen (CN)

(72) Inventors: **Zelong Shao**, Shenzhen (CN); **Huiyue Ze**, Shenzhen (CN)

(73) Assignee: **Aukey Technology Co., Ltd**, Shenzhen (CN)

(**) Term: **15 Years**

(21) Appl. No.: **29/727,664**

(22) Filed: **Mar. 12, 2020**

(51) LOC (13) Cl. **10-04**

(52) U.S. Cl.

USPC **D10/69**

(57) **CLAIM**

The ornamental design for a laser level, as shown and described.

DESCRIPTION

FIG. 1 is front, left and top perspective view of a laser level showing our new design;

FIG. 2 is a rear, right and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

(Continued)

The broken lines in the drawings illustrate the portions of the laser level which form no part of the claimed design.

1 Claim, 8 Drawing Sheets
